RECOVERY OF THE COMPONENTS OF AIR

Claude C. Van Nuys, Greenwich, Conn., assignor
to Air Reduction Company, Incorporated, New
York, N. Y., a corporation of New York

Application July 6, 1945, Serial No. 603,556

1 Claim. (CL 62—175.5)

1

This invention relates to the recovery of components of the atmosphere by liquefaction and rectification of air and particularly to the separation and recovery of oxygen of any desired purity up to about 99.6% and a fraction consisting of the krypton and xenon present in the atmosphere.

No separation of components more volatile than nitrogen is attempted, these components together with most of the argon being combined with the nitrogen which is separated in the initial treatment of the air. The liquid fraction recovered in such initial treatment consists principally of oxygen with krypton-xenon, the latter being recovered as a liquid product after the oxygen has been separated.

It is the object of the invention to provide a simple and economical procedure which permits the continuous recovery of substantially pure oxygen and krypton-xenon in a commercially practicable manner.

Other objects and advantages of the invention will be apparent as it is better understood by reference to the following specification and the accompanying drawing, which illustrates diagrammatically an apparatus suitable for the practice of the method, it being understood that details well known in the art are omitted for the purpose of clarity.

In carrying out the invention, air, initially compressed to a suitable pressure, for example upward to 20 atmospheres, and cooled in the usual intercoolers and exchangers, is subjected to initial separation by liquefaction and rectification to produce an effluent consisting principally of nitrogen, but including components more volatile than nitrogen and also most of the argon. The effluent can be discharged to the atmosphere or delivered to suitable storage facilities after passing through the exchangers where its refrigerative value is recovered. The liquid product obtained in the initial treatment consists principally of oxygen and krypton-xenon, although it may carry small amounts of argon. This liquid is subjected to an auxiliary rectification with selective condensation of the effluent which consists of substantially pure oxygen. The liquid product of the auxiliary rectification is krypton-xenon, which may be withdrawn as desired. The oxygen, after passing through the usual exchangers, can be delivered to suitable storage facilities. In order to maintain the necessary refrigeration in the system, a portion of the high pressure air is diverted to an auxiliary column where it is subjected to selective liquefaction to produce two

2

fractions, one consisting of enriched oxygen liquid and the other consisting of liquefied nitrogen. The latter is utilized as a cooling agent in the selective liquefaction of the effluent from the auxiliary rectification and if desired as a portion of the reflux in the initial separation of the air.

Referring to the drawing, the initial separation is effected in a column consisting of upper and lower rectification columns 5 and 6 and an intermediate condenser section 7. The rectification sections include the usual trays 8 and bubble caps 9. The air, compressed and cooled as hereinbefore described, is introduced through a pipe 10 and delivered through a pipe 11 controlled by a valve 12 to a coil 13 at the bottom of the rectification section 6. Flowing downwardly over the trays 8, the liquid is enriched in oxygen. The vapors rising through the trays pass upwardly through tubes 16 of the condenser section 7 to a head 17, being subjected to partial liquefaction therein. The liquid flows backwardly to the trays. The uncondensed residue, consisting substantially of nitrogen, flows downwardly through the tubes 18 in which the nitrogen is liquefied. The liquid nitrogen accumulates in a collector 19 and is delivered through a pipe 20 and pressure reducing valve 21 to the top of the rectification section 5, affording the reflux liquid necessary to complete the separation. Enriched oxygen liquid is withdrawn from the bottom of the rectification section 6 through a pipe 22 controlled by a valve 23 and is delivered through a pipe 24 and pressure reducing valve 25 to an intermediate level of the rectification section 5. The liquids flowing downwardly through the rectification section 5 are enriched in oxygen and krypton-xenon and accumulate in the condenser section 7. The effluent, consisting of nitrogen, with more volatile constituents such as neon and helium, together with a considerable proportion of the argon, escapes through a pipe 26 and may be discharged or delivered to suitable storage. The rectification to effect initial separation can be conducted at any suitable pressures, for example 5 atmospheres absolute in the rectification section 6 and 1 atmosphere absolute in the rectification section 5.

The liquid from the condenser section 7 is withdrawn through a pipe 27 and flow regulating valve 28 and delivered to an intermediate level of an auxiliary column 29 having the usual trays 30 and bubble caps 31. In flowing downwardly over the trays, the liquid becomes progressively enriched in krypton-xenon, and oxygen vapors rise through the trays and finally enter tubes 32 of a condenser section 33 at the top of the col-

umn. The tubes are surrounded by liquid nitrogen supplied as hereinafter described. The resulting heat exchange between the liquid and vapors ensures liquefaction of krypton-xenon in the vapors so that only oxygen escapes through a pipe 34 from a head 35. Minor amounts of impurities may be present in the oxygen, which however can be produced at any desired purity from 95% to 99.6%. The oxygen is delivered through the usual exchangers to suitable storage facilities.

To afford the nitrogen liquid utilized in the condenser section 33, a portion of the high pressure air is diverted through a pipe 36 and delivered to tubes 37 immersed in the liquid which collects at the bottom of the auxiliary column 29. The air, in passing through the tubes, is liquefied selectively, and an enriched oxygen liquid collects below the tubes 37 and is withdrawn through a pipe 38 and flow regulating valve 39. This liquid joins the liquid in the pipe 24 which is delivered to the rectification section 5 through the pressure reducing valve 25. The residue of the air, consisting substantially of nitrogen, is withdrawn through a pipe 40 and delivered through a flow regulating valve 41 to the tubes 42 of a condenser disposed within the auxiliary column 29 and surrounded by liquid flowing downwardly through the column. The nitrogen is thus liquefied at substantially its initial pressure, i. e., that in pipe 10. It is withdrawn through a pipe 43 and delivered through a pressure reducing valve 44 to the condenser section 33. A portion of the liquid is diverted through a pipe 45 and valve 46 to the top of the rectification section 5, thus restoring to the main column an amount of liquid reflux equivalent to the liquid lost by the main column through pipe 27. The nitrogen vaporized in the condenser 33 is delivered through a pipe 47 to the pipe 26, and thus escapes with the nitrogen product of the separation.

The liquid krypton and xenon which accumulates about the tubes 37 at the bottom of the auxiliary column may be withdrawn as desired through a pipe 48 controlled by a valve 49. It may be delivered to any suitable storage facilities.

The operation as described ensures the effective separation of the air into the desired con-

stituents in a continuous and economical manner. All essential refrigeration for the maintenance of the operation is produced effectively by utilizing the air at the initial pressure in the manner described. An ample supply of liquid nitrogen is available to ensure the removal from the oxygen product of substantially all impurities, particularly krypton and xenon, which is accumulated in liquid form and withdrawn as a separate product. 10 Various changes may be made in the details of the procedure and in the apparatus employed without departing from the invention or sacrificing the advantages thereof.

I claim:

- 15 The method of recovering substantially pure oxygen and krypton-xenon simultaneously from the atmosphere by liquefaction and rectification of air, which comprises subjecting a portion of the air to a primary separation by liquefaction 20 and rectification to produce a gaseous effluent consisting of nitrogen, components more volatile than nitrogen, and a substantial part of the argon present in the air and a liquid consisting principally of oxygen and krypton-xenon, subjecting 25 the liquid to an auxiliary rectification followed by partial condensation of the gaseous effluent therefrom by heat exchange with liquid nitrogen to separate krypton-xenon as a liquid product, providing liquid nitrogen and enriched oxygen liquid by selective condensation of another portion of the air through heat exchange with the krypton-xenon liquid, utilizing a part of the liquid nitrogen so provided in the partial condensation of the gaseous effluent from the auxiliary rectification and utilizing the remainder of the liquid nitrogen and the enriched oxygen liquid in the rectification step of the primary separation.
